UNITED STATES PATENT OFFICE.

WILLIAM L. DALY, OF SCHENECTADY, NEW YORK.

TICKET-HOLDER.

1,087,871.

Specification of Letters Patent. Patented Feb. 17, 1914.

Application filed June 21, 1912. Serial No. 705,091.

To all whom it may concern:

Be it known that I, WILLIAM L. DALY, a citizen of the United States, residing at Schenectady, in the county of Schenectady 5 and State of New York, have invented new and useful Improvements in Ticket-Holders, of which the following is a specification.

This invention relates to ticket holders particularly to combined ticket holders and 10 match scratchers, the principal object of the invention being to provide a simple and convenient device of this character which may be secured to the walls or seats of railway cars for the reception of tickets.

15 A further object of the invention is the provision of a device of this character which may be secured to the seat and which is adapted to receive tickets from either side, whereby the same may be readily used when 20 the seat is turned over or reversed.

Further objects of this invention will appear as the following specific description is read in connection with the accompanying drawing, which forms a part of this 25 application, and in which:

Figure 1 is a top plan view. Fig. 2 is a bottom plan view. Fig. 3 is a side elevation. Fig. 4 is a section on the line 4—4 of Fig. 3.

30 Referring more particularly to the drawing, the device consists of an integral casting having a base piece 1 provided with apertures 2 to receive screws or other suitable fastening devices. Integrally connected to the base plate but separated therefrom is the top piece 2 which produces with the base piece a ticket receiving slot 3 preferably hav-

ing flared entrances at either side thereof. The base piece 1 is recessed, as shown at 4, and is provided with an aperture 5 through 40 which the right angular end of a ticket retaining spring 7 is adapted to pass. The said retaining spring 7 is secured within the recess in any suitable manner and is provided at its free end 6 with a curved round- 45 ed surface, as shown at 8, to produce cam surfaces, said surfaces adapted to engage with the top wall of the receiving slot 3 whereby the ticket may be inserted from either side of the receiving slot without the 50 necessity of employing an additional manipulating member.

What is claimed is:

A device of the class described comprising a base piece, an integral top piece separated 55 therefrom and forming therewith a ticket receiving slot having flared entrances, said base piece being recessed and centrally apertured, and a spring secured in the recess and passing through said aperture into engagement with the upper wall of the top piece at a point medially of the length of the receiving slot and having a curved end to produce opposite cam surfaces whereby the ticket may be inserted from either side without the necessity of employing an additional 60 manipulating member.

65 In testimony whereof I affix my signature in presence of two witnesses.

WILLIAM L. DALY.
